ABSTRACT: A tube heat exchanger with liquid heat carrier includes a cylindrical casing having a pair of partitions, one adjacent each end, defining an upper chamber, a lower chamber, and an intermediate chamber. Inner tubes for conducting fluid to be heated or cooled extend between and through the partitions to interconnect the upper and lower chambers.

TUBE HEAT EXCHANGER WITH LIQUID HEAT CARRIER

BACKGROUND OF THE INVENTION

Tube heat exchangers with liquid heat carrier and having inner tubes carrying the fluid to be heated or cooled, which inner tubes are surrounded by a coaxial covering tube to define an annular channel for the liquid heat carrier, are known. These tube heat exchangers which, in most cases have a plurality of mutually parallel inner tubes enclosed by respective covering tubes, can serve as drop film evaporators, for the concentrating of lye solutions, for example, or for carrying out chemical reactions for preparing phthalic acid anhydride, for example. Thus, they are useable, by way of example, whenever an accurate temperature control along the tube is required and the quantities of heat to be supplied or extracted are large.

It is known, in heat exchangers of this type, to utilize a liquid salt as the liquid heat carrier. This presupposes that the annular channel between the inner tube and the covering tube has a relatively narrow cross section, for example an annular width of about 2-3mm. It is necessary that the channel width be as constant as possible not only in a circumferential direction but also over the entire length of the exchanger. With the high operating temperatures and large temperature differences of such tube exchangers, it is hardly possible to avoid a distortion or twisting of the individual tubes, since the covering tube and the inner tube do not distort to the same degree. This will necessarily lead to uncontrollable changes in the cross section of the annular channels.

Furthermore, with fluid flowing through a bundle of tubes to be heated or cooled by a liquid on the exterior of the tubes, the problem arises of how to carry the liquid in the space surrounding the tubes. If the fluid contained within the tubes is subject to a process which requires an accurate temperature control along the tubes, means for carrying the cooling or heating liquid, in the space surrounding the tubes, must be provided. It is known to use transverse baffle plates for this purpose, and these divert the heat carrier liquid through the length of the vertically arranged tubes and several times at right angles to the tubes. However, an exact temperature control in all tubes and along the axes of the tubes is not possible by this procedure. The conditions become worse the larger the number of tubes and the shorter the length of each tube.

Another procedure for distributing the heat carrier evenly over the space surrounding the tubes comprises providing, centrally of this space, a circulating propeller, and the liquid heat carrier is distributed as uniformly as possible over a perforated plate extending at right angles to the tube axis and with a large number of perforations. With this arrangement, the heat carrier is indeed evenly distributed over the entire cross section of the reactor containing the tubes. However, along the tubes themselves no definite speed of the heating or cooling liquid, and thus no uniform transmission of heat, can be achieved.

These problems arise more particularly, for example, with a reactor for the production of phthalic acid anhydride. In this process, a gas is disposed inside the tubes, and this gas strongly acts over a catalyst and gives off heat. In order that the action can be properly controlled, this heat must be extracted. In practice, reactors with 8,000 tubes are used, and in this case the requirement is that all tubes be cooled uniformly along their length. To that end, a liquid salt, acting as a heat carrier, is circulated through the reactor at a temperature of 450° C. The temperature inside the tubes can rise to 500° C. or more.

To attain uniform cooling of the tubes, the above mentioned transverse baffle plates have hitherto been used, the circulating quantity of cooling liquid necessarily being of such a magnitude that, between the entry and exit of the liquid salt, only a few degrees of temperature difference exists. In spite of this, no assurance can be given that all the tubes are cooled absolutely equally.

SUMMARY OF THE INVENTION

This invention relates to tube heat exchangers with liquid heat carriers and, more particularly, to a novel and improved construction of such heat exchangers.

In accordance with the invention, the above mentioned drawbacks with respect to differential distortion of the inner and covering tubes are avoided by forming the covering tube with indentations of equal radial height distributed along its length and around its circumference. These indentations project into the annular channel for the liquid heat carrier and serve, on one hand, as range spacers to assure a constant cross section of the channel and, at the same time, serve as turbulence producers in the annular channel.

Drawbacks of the known forms of tube heat exchangers of liquid heat carriers are avoided by the present invention in that the bundle of tubes is mounted upright in a cylindrical case between a cover plate and a bottom plate, the opposite ends of the tubes opening outside of these plates. The casing space containing the tube bundle between the cover plate and the bottom plate is subdivided by an intermediate plate or partition into two superjacent chambers, one of which is connected with the inlet for the liquid heat carrier and the other of which is connected with the outlet for the liquid heat carrier. The covering tubes, provided with the aforementioned indentations, extend through the intermediate plate and communicate, on one end, directly below the cover plate and, on the other end, directly above the bottom plate, with a respective one of the two superjacent chambers.

The only connection between the superjacent chambers, and thus between the inlet and outlet of the heating or cooling liquid, lends through the channels formed between the individual tubes and their jackets into which the indentations of the jacket or cover tubes extend to serve simultaneously as range spacers spacing the covering tubes from the inner tubes, and as turbulent producers. The liquid heat carrier thus flows from the relatively large volume inlet chamber into the covering tubes, through the annular channels, and to the outlet chamber. As a result, not only is there a uniform distribution of the liquid heat carrier along all of the covering tubes but also there are equal, turbulent flow conditions along all of the tubes.

An object of the invention is to provide an improved tube heat exchanger utilizing a liquid heat carrier.

Another object of the invention is to provide such a heat exchanger including at least one inner tube for conducting fluid to be heated or cooled, with a covering tube surrounding the inner tube to define an annular channel for the liquid heat carrier and with the covering tube being formed with indentations at substantially equal radial height distributed longitudinally and circumferentially thereof.

A further object of the invention is to provide such a heat exchanger in which a bundle of tubes is mounted upright in a casing between a cover plate and a bottom plate and open into respective top and bottom chambers defined by the cover plate and the bottom plate.

Another object of the invention is to provide such a heat exchanger in which the interior of the casing between the cover plate and the bottom plate is subdivided by an intermediate plate into two superjacent chambers, one connected with the inlet for the liquid heat carrier and the other connected with the outlet for the liquid heat carrier.

A further object of the invention is to provide such a heat exchanger in which the covering tubes, formed with the mentioned indentations, surround the respective inner tubes in the intermediate space and extend through the intermediate plate.

Another object of the invention is to provide such a heat exchanger in which each covering tube opens, at opposite ends, adjacent the cover plate and the bottom plate, respectively, to thus interconnect the two superjacent chambers of the intermediate space.

A further object of the invention is to provide such a heat exchanger in which the indentations in the covering tubes serve not only as range spacers to maintain a uniform cross section of the annular channels but also serve as turbulence producers in the annular channels.

Another object of the invention is to provide such a heat exchanger in which there is a uniform distribution of the liquid heat carrier over the lengths of the tubes and equal, turbulent flow conditions along all of the tubes.

For an understanding of the principles of the invention, reference is made to the following description of a typical embodiment thereof as illustrated in the accompanying drawings.

BRIEF DESCRIPTION OF THE DRAWINGS

In the drawings:

FIG. 1 is a vertical sectional view of a phthalic acid anhydride reactor having a tube heat exchanger embodying the invention;

FIG. 2 is a plan view corresponding to FIG. 1 with the lid of a cylindrical casing removed;

FIG. 3 is a vertical cross section, to a larger scale, illustrating a detail of the tube exchanger shown in FIG. 1; and

FIG. 4 is a transverse sectional view taken along the line A-A of FIG. 3.

DESCRIPTION OF THE PREFERRED EMBODIMENT

Referring first to FIGS. 1 and 2, the illustrated reactor has a cylindrical casing 1 with an outwardly concave or arched cover 1a and an outwardly arched or concave base or bottom 1b, each of which is provided with a respective fluid inlet or fluid outlet. Casing 1 is provided with a substantially horizontal cover plate 3 and a substantially horizontal bottom plate 4, parallel to cover plate 3. A bundle of upright tubes 2 extend between plates 3 and 4 and open therethrough into top chamber 5 and bottom chamber 6. The narrow inner tubes 2 extending between plates 3 and 4 are tightly anchored in these plates, and the plates 3 and 4 define an intermediate space.

In accordance with the invention, the space intermediate plates 3 and 4 is subdivided by an intermediate plate 7 into two superjacent chambers 8 and 9. A lower connection 10 serves as an inlet for the liquid heat carrier into lower chamber 8, while an upper connection 11, which is diametrically opposite lower connection 10, serves as an outlet for the liquid heat carrier from upper chamber 9.

That portion of each tube 2 within chambers 8 and 9 is surrounded by a respective coaxial covering tube 12. Tubes 12 have open top and bottom ends and extend in fluid-tight relation through intermediate plate 7. Each tube 12 opens at its top directly underneath cover plate 3 into outlet chamber 9, and opens at its bottom directly above bottom plate 4 into inlet chamber 8.

As best seen in FIG. 3, the inlet openings 12a of covering tubes 12 are widened in the nature of a funnel. The space between each tube and its respective covering tube 12 is, as compared with the diameter of the tubes and particularly with the tube-free volume of chambers 8 and 9, very small.

To assure a substantially uniform spacing of each covering tube 12 from its associated inner tube 2, each tube 12 is provided with indentations 13, 13a which are distributed over the entire length and entire circumference of the covering tube, these indentations lying substantially against the associated inner tube 2. Indentations 13, 13a succeeding one another in a direction longitudinally of each tube 2 are staggered circumferentially relative to one another. The preferably hemispherical indentations 13, 13a prevent laminar flow from developing in the narrow annular channel between each tube 2 and its covering tube 12. By thus assuring a strongly turbulent flow, especially high heat transmission values can be obtained.

In operation, the above described reactor may include a heat exchanger having as many as 8000 tubes 2. A gas is conducted in tubes 2, and this gas reacts over a catalyst and in the reaction process gives off heat. The heat carrier, which is a

liquid salt at a temperature of 450° C., enters through inlet connection 10 into chamber 8 and distributes itself, in consequence of the large volume of the chamber, at a very low speed over the entire cross section of the chamber. From this reservoir, and having practically the same pressure and the same temperature over its entire cross section, the liquid heat carrier enters the inlet openings 12a of covering tubes 12. The pressure, temperature and speed of the liquid heat carrier in the covering tubes 12 along the inner tubes 2, containing the reacting gas, are thus the same for all of the tubes 12. The strongly turbulent cooling liquid flowing through the covering tubes 12 exits at the upper ends of covering tubes 12 into chamber 9, where the speed of the cooling liquid decreases again so as to be practically negligible. The cooling liquid leaves the reactor through connection 11. Since the two connections 10 and 11 are diametrically opposite each other, the inflow and outflow pressure losses, at right angles to the axes of the tubes, balance each other substantially completely.

The principal advantage of the tube exchanger of the invention is the definite speed and strong turbulence of the liquid heat carrier along the axes of the tubes, and this guarantees a much better heat transfer relative to the reactor tubes than could be obtained with known liquid conducting means. Consequently, smaller heat transmission surfaces can be provided or, with smaller temperature differences, a more uniform cooling or heating can be achieved.

It will be understood that the above described conduction of the heating or cooling liquid, and the design of the covering tube or tubes, can be employed generally wherever a liquid medium for cooling or heating in a tube heat exchanger or an evaporator is used.

While a specific embodiment of the invention has been shown and described in detail to illustrate the application of the principles of the invention, it will be understood that the invention may be embodied otherwise without departing from such principles.

I claim:

1. A tube heat exchanger with liquid heat carrier comprising, in combination, an upright substantially cylindrical casing having its upper end closed by a cover plate and its lower end closed by a bottom plate; a bundle of inner tubes, for conducting liquid to be heated or cooled, disposed in a chamber defined by said casing, said cover plate and said bottom plate, each inner tube extending between said cover plate and said bottom plate and opening exteriorly of these plates; a plate intermediate said cover plate and said bottom plate and dividing said chamber into superjacent upper and lower subchambers, one of said subchambers having a lateral chamber outlet opening and the other of said subchambers having a lateral chamber inlet opening; said plate being formed with apertures each having a respective inner tube extending therethrough; and a bundle of cover tubes disposed in said chamber, with each cover tube surrounding a respective inner tube in coaxially radially spaced relation therewith to define an annular channel for receiving the liquid heat carrier; each cover tube extending through a respective aperture in said intermediate plate and being supported solely by said intermediate plate; the upper end of each cover tube opening into said upper subchamber directly below said cover plate and substantially above the lateral opening in said upper subchamber, and the lower end of each cover tube opening into said lower subchamber directly above said bottom plate and substantially below the lateral opening in said lower subchamber.

2. A tube heat exchanger with liquid heat carrier, as claimed in claim 1, in which said chamber inlet communicates with the lower of said two superjacent subchambers and said subchambers outlet communicates with the upper of said superjacent chambers.

3. A tube heat exchanger with liquid heat carrier, as claimed in claim 2, in which said chamber inlet and said chamber outlet are diametrically opposite each other.

4. A tube heat exchanger with liquid heat carrier, as claimed in claim 3, in which each covering tube has a downwardly

diverging liquid heat carrier inlet which is substantially funnel-shaped.

5. A tube heat exchanger with liquid heat carrier, as claimed in claim 1, in which said heat exchanger includes outwardly convex upper and lower end walls each defining, with the adjacent one of said cover and bottom plates, a chamber having an opening for the supply of fluid to said inner tubes and the extraction of fluid from said inner tubes.

6. A tube heat exchanger with liquid heat carrier, as claimed in claim 1, in which each covering tube is formed with indentations of substantially equal radial height distributed lon-

gitudinally and circumferentially thereof.

7. A tube heat exchanger with liquid heat carrier, as claimed in claim 6, in which said indentations have a substantially hemispherical form.

5 8. A tube heat exchanger with liquid heat carrier, as claimed in claim 7, in which said indentations engage the associated inner tube, and indentations succeeding each other longitudinally of the associated covering tube being staggered circumferentially of the associated covering tube.
